[57] **CLAIM**

The ornamental design for an abrasive sheet with die-cut pattern, as shown and described.

DESCRIPTION

FIG. 1 is a perspective view of an abrasive sheet with die-cut pattern according to my new design;

FIG. 2 is a front view thereof;

FIG. 3 is a rear view thereof;

FIG. 4 is a left side view, which is substantially identical to the right side view;

FIG. 5 is a top view thereof; and,

FIG. 6 is a bottom view thereof.
